Attorney.

UNITED STATES PATENT OFFICE

WILLIAM HUGH CLIFFORD, OF EALING, LONDON, ENGLAND

MEDICAL ELECTRIC LAMP

Application filed September 21, 1928, Serial No. 307,503, and in Great Britain October 14, 1927.

This invention relates to medical arc lamps, and its object is to improve that known type of lamp in which the electrodes are carried horizontally on brackets which can be fed along on cross members at the top of a standard.

An object of the invention is to protect the eyes of the operator from dangerous radiations from the arc or like source.

According to this invention in a lamp of the type having a tubular cross member carrying the electrodes and nuts sliding in the tube, the electrode carrying members are guided on the cross member by means independent of the nuts. The lamp is provided with a cover over the upper part in the form of a roof with sloping sides arranged to cut off lateral and upward radiations without intercepting radiation in the desired direction. It is usually unnecessary for it to cut off downwardly inclined rays.

Where the cover is of metal and any part liable to come into contact with live parts of the lamp, such parts are provided with insulating coverings. The cover may also be provided with windows glazed with material adapted to transmit light rays but to cut off the harmful rays. For example Crookes glass, or fairly deep coloured glass may be used. Preferably, the cover is provided with a light trapped outlet at the top to permit free air circulation.

An embodiment of the invention is illustrated by way of example in the accompanying drawings, in which—

Figure 1 is a front view, partly in section, of the complete lamp, with the cover reflector and screen removed.

Figure 2 is a perspective view of the lamp.

Figure 3 is a plan view of the cover alone, and

Figure 4 is a sectional view on the line I—I of Figure 1.

A tripod 1 as shown or alternatively a heavy base, carries a tubular standard 2 in which can slide an upper tube 3, on which a collar 41 which can be clamped by a set screw 4, for adjustment in height, while allowing tube 3 to rotate freely within the tube 2. At the upper end of the tube 3 is secured a tubular

cross member 5 slotted at each end at the top at 6 and at the bottom at 7. Within the tube 5 at each side, slides a member 8 of circular section with wings 9, 10 fitting respectively in the slots 6 and 7. The members 8 can be fed independently by screws 11, 12 which are preferably of opposite hand, and carry operating heads 13, 14. The caps 38 which form bearings for the screws 11, 12, are screwed on to the ends of the tube 5, while a washer 37 is interposed between the cap and the shoulder on the screw to prevent contraction of the tube due to the presence of the slots, and consequent possible slipping of the cap.

On the outside of the tube 5, two tubular members 15 are provided, the tubes being a good sliding fit and secured to each of the members 8 by screws 16 entering the wings 9, 10. At the inner ends of the members 15 are formed or secured uprights 17 to which are secured insulating members 18. At the upper ends of the members 18 are secured metal half clips 19 provided with terminals 20 to receive the cables for feeding the arc, and to which are hinged spring jaws 21 which with the half clips 19 form the complete clips for taking the electrodes. To insert the electrodes the jaws 21 are opened by depressing the tails 22 against the springs 23. Such clips will of course accommodate electrodes varying considerably in size, while owing to the length of the tubular members 15 the clips can support the electrodes quite close to the arc and the intermediate metal rods formerly used as electrode holders, which could only take one definite size of electrode are no longer required. Furthermore, the provision of double wings on the members 8 prevents any oscillation about the axis of the tube 5 and the length of the tubular members 15 which form the guiding means for the electrode carrying members prevents oscillation about the other two axes at right angles so that the electrodes are always maintained accurately in alignment.

In order to form the rays emitted by the arc into a beam, I provide a reflector 24 and also a frame 25 in which slides a filter screen 45 by which undesirable rays, such as heat,

85

90

95

100

may be filtered off from the beam. The reflector and frame are adjustably carried on a square section bar 26 which passes through the centre of, and is secured to, the tube 5.

- 5 The electrode holders, reflector and filter screen are enclosed in a cover made up of sheet metal with a flat top 51 and symmetrically inclined sides 52. The rear end is closed by a plate 53 and carries a block 54 drilled to 10 slide easily on the upright rod 55 which carries the reflector 24 and provided with a locking screw 56. The plate 53 is cut away at 57 to clear the block 58 carrying the lamp reflector 24.
- 15 At the lower edges of the sides 52, which are liable to come into contact with the electrode holders on the supports 60 during adjustments, insulators 61 are secured in any convenient manner. For example they may be 20 grooved to receive the edges of the sides 52.

The top 51 is centrally perforated and provided with a light-trapping cover 62. The sides are also perforated and the openings provided with guides 63 which receive plates 25 64 of Crookes or coloured glass which are secured by turn buttons 65.

To catch the ash from the arc I provide a tray 27 having an inturned rim to prevent spilling when tilted, beneath the cross tube 5.

30 The tray is conveniently secured by clamping between the parts of the tube 3 which is cut through at 28 and screwed on to a nipple 29.

In order to enable the direction of the beam to be changed, the tube 3 is provided with an 35 articulated joint with its axis parallel with the axis of the tube 5. The joint is conveniently made by forming a flat disc 30 on the upper part, and a flat coating disc 31 on the lower part of the tube 3. The two discs are 40 resiliently pressed together by a spring 32 on a spindle bolt 33. A wing nut 34 allows the pressure to be adjusted so that the upper part of the tube 3 can be swung sufficiently easily about the bolt 33, while the friction is sufficient to maintain the position to which the 45 joint has been set. Clamping and unclamping to adjust the joint are therefore unnecessary. For convenience in operation, the disc 30 is provided with a handle 35.

50 In order that the whole lamp may be readily moved about, the main standard is provided with a handle 36. As the complete lamp is fairly heavy and it is essential that it should be held substantially vertical during movement in order to prevent spilling of ash or 55 risk of breakage of the screen, the handle is directed horizontally so that the hand occupies the most effective and natural position when the standard is vertical and there is no 60 tendency for the whole to tilt over when it is lifted.

What I claim is:—

1. A medical arc lamp comprising a standard, an electrode support mounted at 65 the top of said standard, electrode carrying

members slidably mounted on said support, a cross bar on said standard set at right angles to said support, a reflector mounted at one end of said cross bar, a filter frame mounted at the other end of said cross bar and a cover mounted on said cross bar adapted to fit over said members and to cut off lateral and upward radiations without intercepting radiation in the desired direction. 70

2. A medical arc lamp comprising a standard, an electrode support mounted at 75 the top of said standard, electrode carrying members slidably mounted on said support, a cross bar on said standard set at right angles to said support, a reflector mounted at one end of said cross bar, a filter frame mounted at the other end of said cross bar and a cover mounted on said cross bar in the form of a roof with sloping sides adapted to fit over said members and to cut off lateral and upward radiations without intercepting radiation in the desired direction. 80

3. A medical arc lamp comprising a standard, an electrode support mounted at the top of said standard, electrode carrying 85 members slidably mounted on said support, a cross bar on said standard set at right angles to said support, a reflector mounted at one end of said cross bar, a filter frame mounted at the other end of said cross bar, a cover mounted on said cross bar in the form of a roof with sloping sides adapted to fit over 90

said members and to cut off lateral and upward radiations without intercepting radiation in the desired direction and insulated edge pieces adapted to protect those portions of said cover which may come into contact with live parts of the lamp. 95

4. A medical arc lamp comprising a standard, an electrode support mounted at the top of said standard, electrode carrying members slidably mounted on said support, a cross bar on said standard set at right angles to said support, a reflector mounted at one end of said cross bar, a filter frame mounted at the other end of said cross bar, a cover mounted on said cross bar in the form of a roof with sloping sides adapted to fit over said members and to cut off lateral and upward radiations without intercepting radiation in the desired 100 direction said sloping sides having openings glazed with a glass adapted to transmit light rays but to cut off harmful radiation. 105

5. A medical arc lamp comprising a standard, an electrode support mounted at 110 the top of said standard, electrode carrying members slidably mounted on said support, a cross bar on said standard set at right angles to said support, a reflector mounted at one end of said cross bar, a filter frame mounted at the other end of said cross bar and a cover mounted on said cross bar in the form of a roof with sloping sides adapted to fit over 115 said members and to cut off lateral and upward radiations without intercepting radiation 120

125

130

tion in the desired direction, said cover having a light trapped ventilating opening at the top.

6. A medical arc lamp of the type set forth comprising a standard, a tubular cross member mounted at the top of said standard, electrode carrying members slidably mounted on said tubular cross member, a cross bar on said standard set at right angles to said tubular member, a reflector mounted at one end of said cross bar, a filter frame mounted at the other end of said cross bar, a cover mounted on said cross bar in the form of a roof with sloping sides adapted to fit over said members and to cut off lateral and upward radiations without intercepting radiation in the desired direction and insulated edge pieces attached to edges of said sloping sides adapted to protect those portions of the cover which may come into contact with live parts of the lamp, said cover having openings in its sloping sides glazed with a glass adapted to transmit light rays but to cut off harmful radiation and light trapped ventilating openings at the top.

In testimony whereof I have signed my name to this specification.

WILLIAM HUGH CLIFFORD.
